CLAIM

The ornamental design for a kitchen tool with curved handle, as shown and described.

DESCRIPTION

FIG. 1 is a perspective view of a kitchen tool with curved handle according to the present invention;

FIG. 2 is another perspective view of the kitchen tool with curved handle of FIG. 1;

FIG. 3 is a top view of the kitchen tool with curved handle of FIG. 1;

FIG. 4 is a bottom view of the kitchen tool with curved handle of FIG. 1;

FIG. 5 is a first side elevational view of the kitchen tool with curved handle of FIG. 1;

FIG. 6 is an opposite side elevational view of the kitchen tool with curved handle of FIG. 1;

FIG. 7 is a first end view of the kitchen tool with curved handle of FIG. 1;

FIG. 8 is an opposite end view of the kitchen tool with curved handle of FIG. 1; and,

FIG. 9 illustrates a distal end of the kitchen tool with curved handle of FIG. 1 being inserted into a jar, shown in broken lines, by a person's hand, also shown in broken lines.

The objects shown in broken lines are shown for environmental purposes only and form no part of the claimed design.
